Primary Examiner — Elizabeth A. Albert

(74) Attorney, Agent, or Firm — Bruce Stone LLP;
Joseph Bruce(57) **CLAIM**

The ornamental design for a tape dispenser, as shown and described.

DESCRIPTION

FIG. 1 is a front perspective view of a tape dispenser showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another front perspective view thereof.

The broken lines in the drawings are for the purpose of illustrating parts of the tape dispenser and a roll of tape that form no part of the claimed design.

1 Claim, 8 Drawing Sheets---
